CLAIM

The ornamental design of a pet treat, as shown and described.

DESCRIPTION

FIG. 1 is a top perspective view of a pet treat;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines in the figures are for the purpose of illustrating unclaimed portions of the pet treat and form no part of the claimed design.

1 Claim, 7 Drawing Sheets# US D930,323 S
